DESIGN FOR A WING NUT

Otto Gries, New Rochelle, N. Y., assignor to Crown
Fastener Corporation, Warren, R. I.

Application April 10, 1947, Serial No. 138,282

Term of patent 14 years

(Cl. D54—9)

To all whom it may concern:

Be it known that I, Otto Gries, a citizen of the United States, residing at New Rochelle, in the county of Westchester and State of New York, have invented a new, original, and ornamental Design for a Wing Nut, of which the following is a specification, reference being had to the accompanying drawing, forming part thereof.

Figure 1 is a side elevation of a wing nut showing my new design.

Figure 2 is a bottom plan view of the same.

Figure 3 is a top plan view of the same; and Figure 4 is a side elevation of the same.

I claim:

The ornamental design for a wing nut, as shown.

OTTO GRIES.
